(57) CLAIM

The ornamental design for a shoe, as shown and described.

DESCRIPTION

FIG. 1 is a front view of a shoe;

FIG. 2 is a rear view thereof;

FIG. 3 is a top view thereof;

FIG. 4 is a bottom view thereof;

FIG. 5 is a left side view thereof;

FIG. 6 is a right side thereof; and,

FIG. 7 is an isometric view thereof.

The broken lines depicting the sole on the bottom of the shoe in FIG. 4 form no part of the claim.

1 Claim, 7 Drawing Sheets
